DESCRIPTION

FIG. 1 is a perspective view of compartment of ultrasonic diagnostic equipment, showing a new design;
FIG. 2 is a front elevational view thereof;
FIG. 3 is a rear elevational view thereof;
FIG. 4 is a left side elevational view thereof;
FIG. 5 is a right side elevational view thereof;
FIG. 6 is a top plan view thereof;
FIG. 7 is a bottom plan view thereof; and,
FIG. 8 is a cross-sectional view taken along line 8-8' of FIG. 6.

The broken lines are included for the purpose of illustrating portions of the compartment of ultrasonic diagnostic equipment that form no part of the claimed design.
